UNITED STATES PATENT OFFICE

WILLIAM H. LADD, OF LONG BEACH, CALIFORNIA

MARINE RESCUE AND SALVAGE OUTFIT

Application filed May 6, 1929. Serial No. 360,826.

The present invention relates to an outfit for marine rescue and salvage of sunken vessels and has for its primary object to provide a group of boats which may be arranged in such a manner as to efficiently and effectively raise a sunken vessel and possess means for supporting the sunken vessel so that the same may be brought safely into port.

Another very important object of the invention resides in the provision of a boat with a plurality of beams projecting therefrom beyond one side thereof with pulleys in the beams and the cables trained over the pulleys in combination with winch and operating means therefor so that the cables may be utilized in raising a sunken vessel.

A still further very important object of the invention resides in the provision of a boat for rescue and salvage purposes of this nature which may be manufactured at a relatively low cost, may be easily operated and maneuvered, and is otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a top plan view of a plurality of my rescue boats arranged about a sunken vessel which has been raised,

Figure 2 is an end elevation thereof,

Figure 3 is a top plan view of one of the boats,

Figure 4 is a transverse section therethrough,

Figure 5 is a detail longitudinal section showing the winches and the common shaft therefor,

Figure 6 is a perspective view of one of the beams,

Figure 7 is a perspective view showing one end of a member for engaging the submarine, and

Figure 8 is a perspective view showing the other end thereof for engagement with the longitudinal beam of one of the boats.

Figure 9 is a detail horizontal sectional view through a longitudinal beam.

Referring to the drawing in detail, it will be seen that in my rescue and salvage outfit I utilize a plurality of boats 5. I shall first describe one of these boats in detail as they are identical except as will be hereinafter pointed out.

In each boat there is mounted a longitudinal beam 6 extending slightly to one side of the longitudinal center of the boat and a plurality of beams 7 extending laterally therefrom across the center and beyond the side of the boat.

These transverse beams 7 are arranged in pairs and between each pair there is mounted a pair of sheaves 8 and 9, the former adjacent the beam 6 and the latter out beyond the side of the boats. The beams 7 are braced in respect to each other by means of rods 10 and are braced in respect to the side of the boat from which they extend by rods 11.

Cables 12 are trained over the sheaves 8 and 9 and extend down into the boat to be windable on winches 14. These winches 14 are mounted to rotate with a shaft 15 journaled in suitable bearings 16 and the shaft 15 has a chain and sprocket connection 17 with an engine or other prime mover 18.

The only difference between the boats is in the length of the beams 7 and the sides beyond which these beams project and these differences will become immediately apparent from an inspection of Figure 1. In Figure 1 it will be noted that I use three boats to each side of the sunken vessel 19 with the beams pointing toward said vessel 19.

The cables 12 are let down and extended under the vessel 19 and tied together by a diver. Then the shafts 15 are brought into operation and the cables wound on the winches 14 to raise the sunken vessel. When the sunken vessel has reached the surface of the water I then utilize a plurality of spacing and stabilizing members 20, two for each boat 5.

Each member 20 includes an elongated body having a relatively long downwardly directed lateral extension 21 at one end and

a relatively short downwardly extending extension 22 at the other end.

A keeper 23 is mounted on the beam 6 to receive the extension 22 and a keeper 24 is fixed to the vessel 19 to receive the extension 21. The extension 21 is braced in respect to the elongated body of the member 20 by means of a rod 25.

With the vessel 19 supported in this manner it will be seen that the vessel along with the boats 5 may be readily towed into port.

It is thought that the construction, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

In an outfit of the class described, a boat, a beam extending longitudinally of the boat adjacent the center thereof, a plurality of transverse beams projecting from one side of the first beam laterally out beyond one side of the boat, said transverse beam being disposed in pairs, sheaves mounted for rotation between the beams of each pair adjacent the opposite ends thereof, cables trained over said sheaves, a shaft journaled in the boat and having a plurality of winches thereon on which said cables are windable, a prime mover, and chain and sprocket mechanism connecting the prime mover and the shaft, and horizontal crossed brace rods secured at their opposite ends to the inner and outer ends of the transverse beams and brace rods secured to the outer end portions of the beams and to the adjacent side of the boat.

In testimony whereof I affix my signature.

WILLIAM H. LADD.
